UNITED STATES PATENT OFFICE

129,915

DESIGN FOR A SPECTACLE FRAME

Arthur Blum, Brooklyn, N. Y.

Application January 31, 1941, Serial No. 98,620

Term of patent 7 years

To all whom it may concern:

Be known that I, Arthur Blum, a citizen of the United States, residing at 2246 Ocean Avenue, Brooklyn, in the county of Kings and State of New York, have invented a new, original, and ornamental Design for a Spectacle Frame, of which the following is the specification, reference being had to the accompanying drawing, forming part thereof.

Fig. 1 is a front elevational view of a spectacle frame showing my new design, and

Fig. 2 is a plan view of the same.

I claim:

The ornamental design for a spectable frame, as shown.

ARTHUR BLUM.
